UNITED STATES PATENT OFFICE.

FREDERICK G. SCHWEISTHAL, OF CHICAGO, ILLINOIS, ASSIGNOR OF ONE-HALF TO
GEORGE BROMMERSBERGER, OF CHICAGO, ILLINOIS.

CARBURETER.

1,261,959.

Specification of Letters Patent. Patented Apr. 2, 1918.

Application filed May 20, 1916. Serial No. 98,715.

To all whom it may concern:

Be it known that I, FREDERICK G. SCHWEISTHAL, a citizen of the United States, residing at Chicago, in the county of Cook and State of Illinois, have invented certain new and useful Improvements in Carbureters, of which the following is a specification.

This invention relates to carbureters of the type embodying a primary air supply, auxiliary or secondary air supply, a fuel nozzle, and a gas outlet, from which the carbureted air is conducted to the engine, each source of supply being provided with a valve to control the supply.

The present carbureter contemplates the operation of the throttle butterfly valve, the auxiliary or secondary air butterfly valve and the needle valve controlling the gas supply in unison so that as the speed of the engine is increased by the throttle control, the supply of air and of fuel is positively increased in proportion to the amount of mixture or carbureted air supplied to the engine. That is to say, as the throttle butterfly valve is opened to supply more mixture or carbureted air to the engine, the needle valve and the auxiliary air supply valve are similarly, simultaneously, and proportionately opened.

The present invention also contemplates an independent adjustment of the needle valve which controls the fuel supply, in order that it may be regulated independently of the throttle control.

With the above and other objects in view, as will be apparent, this invention consists in the construction, combination and arrangement of parts all as hereinafter more fully described, claimed and illustrated in the accompanying drawings, wherein—

Figure 1 is a top plan view of a carbureter constructed in accordance with the present invention.

Fig. 2 is a central vertical, longitudinal section.

Fig. 3 is a detail of the throttle control, illustrating the adjustable stop used in conjunction therewith.

Fig. 4 is an end elevation of the intake end of the auxiliary or secondary air supply, and illustrates the details in construction of the shutter controlling the same.

Fig. 5 is a side elevation thereof.

Fig. 6 is a horizontal section along line 6—6 of Fig. 2.

Reference being had more particularly to the drawings, 10 indicates the carbureter bowl inclosing the float chamber 11, from one side of which projects the fuel inlet nipple 12, exteriorly threaded for securing the supply pipe thereto. Adjacent to the nipple 12 is a pivot 13 which acts as a support for the arms 14, said arms carrying the float 15 concentrically arranged with respect to the float chamber 11. The outer ends of the arms 14 carry the valve 16 by means of the bearing 17 for the reception of the valve stem, the latter being held in place by the nut 18. The valve 16 is seated in the inner end of the passage of the nipple 12 when the float is elevated and as the float drops, the valve is unseated permitting a quantity of fuel to flow through the nipple 12 into the float chamber 11.

A shell 19 is located concentrically within the float chamber 11, and is encircled by the float 15, said shell being tubular except adjacent to its lower end, where it is provided with a partition 20. A transverse passage 21 is formed in the partition 20 and communicates at each end with the float chamber to form a means of communication between said float chamber and the mixing chamber, which is contained within the shell 19. The fuel nozzle 22 is threaded into the partition 20 midway of the length of the passage 21, and is provided with a conical passage 23 which communicates with said passage 21, thereby creating a means whereby the fuel within the float chamber may enter the passage 21, whence it escapes through the passage 23 to the carbureting chamber 24 at the upper end of the nozzle 22. The lower end of the shell 19 which projects through the base of the bowl 10 is provided with a shoulder 25 which rests flush against the exterior surface of said bowl.

Concentrically formed in connection with the partition 20 is a stud 26 projecting beyond the terminal of the shell 19, said stud being provided as a means for securing the primary air supply pipe 27 to the carbureter. This supply pipe is orificed to receive the projecting end of the shell 19 as illustrated in Fig. 2, while the stud 26 pierces the terminal of said pipe and projects beyond the same. The projecting end of the stud

- 26 has a nut 28 threaded thereon which rests against the outer side of the primary air supply pipe 27 and locks the same upon the stud so that the upper side of the pipe is 5 securely held against the bottom of the bowl 10 and embraces the projecting end of the shell 19. The primary air supply is provided with the usual valve 29, which controls the flow of air therethrough.
- 10 In order that the primary air supply may have access to the carbureting chamber 24, the partition 20 is pierced by the conduits 30 on each side of the passage 21 so that the air from the primary air supply pipe 27 15 enters the mixing chamber below the terminal of the nozzle 22 and mixes with the fuel ejected from the passage 23 of said nozzle at a point adjoining the terminal of the nozzle.
- 15 The interior of the upper end of the shell 19 is threaded for the reception of the tubular exteriorly threaded stud 31 which carries the transversely arranged, elongated casing 32 at its outer end. The mixture of 20 air and fuel is conducted from the carbureting chamber 24 through the tubular stud 31 to the casing 32. One end of this casing curves upwardly as at 33, and terminates in an elliptical plate 34, by means of which 25 this end of the casing 32 is secured to and connects with the manifold, (not shown). This is the gas outlet and is controlled by the throttle butterfly valve 35, which is carried by the valve stem 36 vertically ar- 30 ranged within one end of the casing 32, and projecting through the upper portion of the wall thereof.
- 35 The opposite end of the casing 32 constitutes the auxiliary air inlet, and is con- 35 trolled by the auxiliary or secondary air butterfly valve 37, which is carried by the valve stem 38. Like the valve stem 36, the stem 38 is arranged transversely of the casing 32 and projects through the upper portion of 40 the wall thereof, said stem resting approxi- 40 mately parallel to the stem 36. This secondary or auxiliary air inlet end of the casing 32 is surrounded by an elliptical plate 39 to which is secured the stationary shutter plate 45 40, the same being held in position by screws or other detachable means, and is provided with the central openings 41, whereby the secondary or auxiliary air may pass through the plate. At the point where the openings 50 41 converge is located a pivot pin 42, which projects inwardly from the center of the plate 40, where it carries the pivotally mounted shutter 43 adapted to oscillate on the pin. A series of openings 41^a similar to 55 the openings 41 of the plate 40 are provided in the shutter and are adapted to register, when desired, with the openings 41 of the plate 40. The oscillation of the shutter 43 upon its pivot regulates the quantity of air 60 upon its pivot regulates the quantity of air 65 which can pass through the openings 41 by
- reason of the fact that the solid portions of the shutter 43 may, by the latter's oscillation, partially or wholly close the openings 41. In order to provide a means for holding the shutter plate 43 in any of its adjusted positions, a boss 44 projects from one side of the plate or flange 39, and co-operates with an extension 45 projecting from the shutter 43, said extension resting flush upon the boss 44, and adapted to oscillate thereacross. A 70 curved slot 46 is provided in the extension 45, and receives a screw 47, which passes through said slot and is threaded into the boss 44. It becomes manifest that after the shutter 43 has been adjusted to the desired position to regulate the flow of air through the openings 41, the screw 47 may be tightened, thus fixing the shutter in such adjusted position.
- 75 The protruding end of the throttle valve 80 stem 36 has the throttle control lever 48 secured thereto so that the movement of said lever regulates the angle of the butterfly valve 35 to the vertical plane, and thus controls the amount of carbureted fuel passing 85 to the motor or engine. Superposed above that portion of the control lever 48 embracing the stem 38 is a toothed segment 49. The valve stem 38 of the butterfly valve 37 is provided with a sleeve 50, above which is a 90 toothed segment 51, similar to the segment 49, and in the same horizontal plane there- 95 with. These segments 49 and 51 are provided for the simultaneous and proportion- 100 ate adjustment of the butterfly valves 35 and 37, whereby the amount of auxiliary or sec- 105 ondary air is increased simultaneously and proportionately to the amount of carbureted fuel supplied to the engine.
- 105 As is usual in carbureters, the flow of fuel from the fuel nozzle 22 is controlled by a needle valve 52, which at its lower end seats in the conical passage of the nozzle 22, and regulates the flow of fuel therefrom in pro- 110 portion to the amount of the passage 23 closed by the inner end of said needle valve. The outer end of the needle valve is provided with a knurled disk 53 for the manual adjustment of said valve. An interiorly threaded tubular extension 54 is formed 115 from the upper portion of the wall of the casing 32, and constitutes a bearing through which the needle valve operates. An exteriorly threaded bushing 55 is threaded into this bearing 54 and carries the spur gear 56 at its upper terminal, said spur gear meshing with the segments 49 and 51. This bushing 55 is provided with a central interiorly threaded passage, through which the needle valve stem 52 passes, said stem being 120 provided with the threaded portion 57 for co-operating with the threads of the passage within the bushing. Obviously, a rotary movement imparted to the knurled disk 53 125 will cause the stem of the needle valve 52 to 130

rotate within the bushing 55, thereby manually adjusting the valve independently of any movement on the part of the bushing. In order to lock the needle valve with respect to the bushing after it has been initially adjusted, a lock nut 59 is provided on the outer end of the threaded portion 57 of the needle valve, so that it may be tightened against the gear 56 of the bushing. After the needle valve 52 has been initially and manually adjusted, a movement of the throttle control lever 48 adjusts not only the throttle valve 35, but also through the segment 49, meshing with the gear 56 of the bushing 55, adjusts said bushing so that the needle valve is simultaneously and proportionately adjusted with the throttle butterfly valve 35. The movement of the gear 56 and the bushing 55 clearly imparts a similar movement to the segment 51, which meshes with the gear 56 to adjust the secondary or auxiliary air inlet valve 37 as heretofore described.

The throttle control lever 48 is provided with a right-angular extension 60 through which is threaded a screw 61, said screw being held fixed with respect to the extension 60 by means of the lock-nut 62 mounted on the stem of the screw, between the head thereof and the extension 60. The projecting free end of this screw 61 co-operates with a stationary rib or cam 63 formed on the bearing 54, and constitutes a stop for the throttle control lever 58, the amount of

movement of said lever being limited when 66 the stop contacts with the rib or cam 63. This limit, of course, may be increased or decreased by the adjustment of the screw 61.

What is claimed is:

1. In a carbureter, the combination with a 40 casing with a bearing thereon, of a bushing threaded within said bearing, a fuel valve operating in said bushing, a throttle valve on one side of said bearing, an auxiliary air valve on the opposite side of said bearing, 45 gears on the stems of said throttle and auxiliary air valves respectively, a gear on the bushing aforesaid meshing with the gears on the stems of the throttle and air valves, a stop upon said bearing, a throttle control 50 lever fixed to the stem of the throttle valve for the operation of the gears aforesaid, and an adjustable stop carried by said lever for co-operation with the stop on said bearing.

2. In a carbureter, the combination with 65 a casing, of a bearing projecting therefrom, a bushing threaded into said bearing, a fuel valve threaded into said bushing, a throttle valve upon one side of said bearing, an auxiliary air valve upon the other side of said 60 bearing, the stems of said valves protruding from the casing substantially parallel to the bearing aforesaid, a gear fixed to said bushing, and gears carried by the projecting stems of the throttle and auxiliary air valves 65 respectively and meshing with the gear on the bushing.

FREDERICK G. SCHWEISTHAL.
